UNITED STATES PATENT OFFICE.

JULIUS BRENZINGER, OF FAIRFIELD, CONNECTICUT, ASSIGNOR TO THE MAX AMS MACHINE CO., OF BRIDGEPORT, CONNECTICUT, A CORPORATION OF NEW YORK.

CAN-HEADING MACHINE.

1,369,005.

Specification of Letters Patent. Patented Feb. 22, 1921.

Application filed December 9, 1918. Serial No. 265,855.

To all whom it may concern:

Be it known that I, JULIUS BRENZINGER, a citizen of the United States, residing at Fairfield, in the county of Fairfield and 5 State of Connecticut, have invented certain new and useful Improvements in Can-Heading Machines, of which the following is a specification.

This invention relates generally to can 10 heading machines, with more particular reference to machines primarily adapted to be operated by hand.

In a co-pending application, filed by me November 10, 1917, Serial No. 201,270, I 15 have shown and described a hand-operated can heading machine—although possessing some important features which doubtless might just as successfully be applied to an automatic machine—and in my earlier application I explained in detail the uses and 20 essentials of such a machine. The present invention still more particularly contemplates further improvements in the machine of my earlier application aforesaid.

25 As is well known in this art, the seaming rollers of the most extensively used types of can heading machines are relatively adjusted and operated to perform the seaming operation in a given number of revolutions—30 either of the rollers around the stationarily supported can parts or of the supported can parts relative to the rollers—and after completion of the seaming operation the rollers are withdrawn from the headed can in order 35 to permit the removal of the latter from the seaming mechanism and the positioning of assembled can parts for the next succeeding heading operation. Thereupon, the rollers are returned to effectively operative 40 positions.

In power driven or so-called automatic machines, withdrawal and return of the rollers is properly timed without the necessity for the exercise of any mental effort on part 45 of the operator. It will be apparent, however, that in connection with a machine designed and adapted to be operated by hand, such as that shown and described in my earlier application aforesaid, the operator

50 must note the positions of the seaming rollers with respect to the chuck, in order that the headed can may be removed and another work unit positioned while the rollers are at maximum distances from the chuck. If 55 the operator possesses a fair degree of skill,

this withdrawing and replacing operation may be readily performed without stopping the machine; if he is unskilled, the machine may be momentarily stopped. In either case, this necessity for the exercise of close 60 attention and judgment has a decided tendency to curtail both the effectiveness of the operator and the output capacity of the machine. In the absence of close attention and good judgment, the operator is very likely 65 to attempt withdrawal of the headed can prematurely, before the rollers have been retracted a sufficient distance from the chuck to permit of ready removal of the headed can, or he is just as likely to continue revolution of said rollers until they have started upon their return movement toward the chuck and approach the latter closely enough to interfere with the can withdrawing and positioning operations.

75 The principal object of the present invention is the provision of means—primarily in connection with a hand-operated machine, substantially such as shown and described by me in my co-pending application aforesaid—for automatically controlling the timing of the retracting and returning movements of the seaming rollers, thereby eliminating the necessity for constant close attention by the operator to the positions of 80 the rollers with relation to the chuck and the possibility of insufficient or excessive movements. Incidental to the above, I have in view certain minor improvements designed to enhance the convenience, simplicity, effectiveness, durability and dependability of a machine of the character set forth, 85 as will appear from the following description.

90 My invention will be more readily understood by reference to the accompanying drawings, forming a part of this specification, in which I have shown a practical and convenient embodiment of the invention and in which—

100 Figure 1 is a front elevation, partly in section; the seaming rollers being in what may be termed normal, open or ineffectively operating positions;

Fig. 2 is a vertical transverse section, 105 taken substantially on the line 2—2 of Fig. 1;

Fig. 3 is a top plan view;

Fig. 4 is a horizontal section, taken substantially on the line 4—4 of Fig. 1;

110

Fig. 5 is a view similar to Fig. 4, but with the handle and ratchet in the positions taken immediately following the seaming operation and prior to withdrawal of the rollers 5 to their maximum retracted positions, and

Fig. 6 is a vertical section, taken substantially on the line 6—6 of Fig. 2.

Referring now to the drawings in detail, I have shown therein a frame which comprises the vertical rods or posts 11 and 12 and the cross-bars or braces 13 and 14. The cross-bar 13 is provided at one end with a horizontal arm or plate 15 to which is secured the base 16 of the bracket or standard 15 17 in which is journaled the main driving shaft 18. At the outer end of this shaft 18 is mounted the crank-wheel 19 which, while provided with the usual handle 20, for hand operation, I have also shown in the form of 20 a grooved pulley whereby, if desired, well-known connections may be made with any suitable source of power. The strength and rigidity of the frame is augmented by elongating the rod or post 11 and providing an 25 upper cross-bar or brace 21 between the upper end of the rod or post 11 and the upper end of the bracket 17.

The chuck 22, which receives the can head and supports the assembled can parts during 30 the seaming operation, is mounted at the lower end of the shaft 23. This shaft 23 is rotatively supported by the combined spur and bevel gear 24 keyed to the upper end thereof which rests upon the hub 25 of 35 a mutilated ratchet 26 (and upon the upper end of the sleeve 27 to which said ratchet is keyed). The ratchet 26, in turn, is supported from the cross-bar or brace 13 through the interposition of what for the 40 time being I shall call a collar 28. At the inner end of the shaft 18 is mounted the bevel gear 29 the teeth of which are in mesh with the teeth of the beveled portion of the gear 24, wherefore, as will be apparent, the chuck-shaft 23—and therewith the chuck 22—will be relatively slowly rotated upon rotation of the wheel 19.

The sleeve 27 is suitably journaled in the cross-bar or brace 13 and is rotatively supported from the chuck 22, preferably through the interposition of a well-known form of anti-friction device, as shown. At the lower end of the sleeve 27 is provided the circular eccentric-head 30 upon which is 50 journaled the disk 31. This disk 31 carries the seaming rollers 32 and 33. The manner in which these rollers are mounted and the operation thereof upon relative rotation between the shaft 23 and the sleeve 27 55 is clearly shown and described in my co-pending application aforesaid, the seaming mechanism of the machine of which is identical to the seaming mechanism of the machine of this application, and in greater detail in my prior Patent No. 1,167,346, taken

in connection with another prior Patent, No. 1,167,347, both granted to me January 4, 1916. For the purposes of this description, therefore, it will suffice to state that upon relative rotation between the shaft 23 and the sleeve 27 the seaming rollers are reciprocated to and from effectively co-operative 70 positional relationship with the chuck 22 to successively perform a seaming operation.

As hereinbefore suggested, relative rotary movement between the rollers 32 and 33 and the chuck 22, with the parts in such effectively co-operative positional relationship, must be continued throughout what has the effect of being a certain number of 80 revolutions of said rollers around the chuck in order to complete hermetic seam between the head or cover and the body portion of the can, after which continued operation for a certain period is necessary in order to 85 withdraw the rollers for the removal of the headed can and the positioning of assembled parts to be seamed, and to return the rollers to effectively operating relative positions. It is now desired to insure against the possibility of either excessively prolonging or curtailing this continued operation in an effort to determine when the rollers are at 90 proper distances from the chuck to permit of ready removal of the headed can and substitution of assembled parts to be seamed—certainly a most desirable feature when the machine is operated by hand, and doubtless an absolutely essential feature when the machine is power-driven.

At the lower ends of the rods or posts 11 and 12, below the cross-bar 14, is mounted—preferably in a manner which will be hereinafter described—what may be termed a combined gear-box and supporting plate 34. 10 Journaled in a bearing-block 35 on the gear-box 34 and in an arm 36 projecting from the cross-bar 13 is the vertical shaft 37. This shaft 37 is relatively rapidly driven with relation to the chuck-shaft 23 by means 11 of the pinion 38 the teeth of which are in mesh with the teeth of the spur portion of the gear 24. On the shaft 37, below the pinion 38, is mounted the eccentric 39 on which is journaled the collar 40 carrying the pawl 41. These parts are so located and adjusted that the pawl 41 is adapted to engage the teeth of the mutilated ratchet 26. It will be apparent that upon rotation of the shaft 37 the eccentric 39 will effect reciprocation of 12 the pawl 41 to rotate the ratchet-wheel 26 in a step-by-step movement throughout the toothed portion thereof.

As has been explained, the mutilated ratchet 26 is keyed to the sleeve 27, and it 12 will now be apparent that upon rotation of the driving shaft 18 the chuck-shaft 23 will be relatively rapidly rotated in one direction and the sleeve 27 on said shaft relatively slowly rotated in the opposite direction. In 130

precisely the same manner as that described in my co-pending application and my earlier patents, aforesaid, rotation of these parts effect not only relatively rotary movement 5 between the chuck-supported can parts and the seaming rollers, essential to the seaming operation, but it also properly timed withdrawal of the rollers to maximum distances from the chuck. If rotation of the sleeve 10 27 were continued, the rollers would now be at once returned to effectively operative positions, but relatively slowly enough to entail the loss of considerable time, in the aggregate.

15 It is my purpose not only to check the seaming rollers against return movement when they have been withdrawn to maximum distances from the chuck, and thus provide as much time as may be desired or 20 is necessary to remove the headed can and position a new work unit, but also to provide means for more rapidly reestablishing effectively coöperative positional relationship between rollers and chuck for the next succeeding 25 seaming operation. For this purpose, the part to which I have hereinbefore referred as the collar 28, instead of being annular, is in the form of a closed yoke at the end of an arm or lever 42 projecting to accessible position 30 in front of the machine. The arms of the yoke embrace and are rotatable on the sleeve 27, and are of such length as to permit of slight longitudinal movement of the lever 42 as well as rotation thereof. On the 35 lower face of the ratchet 26 is mounted an open ring 58, providing a notch 59 adapted to be engaged by a lug 60 on the upper face of the lever 42, whereby movement of said lever from the position indicated in Fig. 5 to 40 the position indicated in dotted lines in Fig. 4, with the lug 60 in the notch 59, will rotate the ratchet 26 in the same direction through a corresponding arc and thus rapidly return the rollers to effectively operative 45 positions. I have shown the end 61 of the ring 59 beveled or tapered, and the contiguous side of the lug 60 correspondingly beveled or tapered, whereby the manual forces applied to said lever to return the 50 same to initial position also operate to disengage said lug from the notch to permit of such return without the necessity for the application of specially directed forces.

The teeth of the mutilated ratchet 26 55 extend throughout an arc of just sufficient length to effect rotation of the sleeve 27 by the pawl 41 during the predetermined number of revolutions of the shaft 23 deemed to be requisite to complete the seaming operation and long enough thereafter to withdraw the rollers to maximum distances from the chuck. The parts are now in the relative 60 positions indicated in Fig. 5. When the headed can has been removed and a new 65 work unit positioned, the operator grasps

the arm or lever 42 and swings the same to the position indicated by the dotted lines in Fig. 4. This brings the first of the series of teeth on the ratchet again into engagement with the pawl 41, and when the arm or lever 70 42 is now swung back to its initial position the arms of the yoke 28 will slip on the sleeve 27 which is checked against movement in this direction. Properly assembled can parts having been positioned in the interim, 75 the automatic step-by-step rotation of the sleeve 27 is now repeated and another seaming operation performed.

The machine of my invention is provided with the usual supporting platform for the 80 can parts which is vertically reciprocable to raise the positioned work unit to engagement with the chuck and lower the headed can therefrom. I have shown this platform in the form of a disk 43 having a hub 44 secured at the upper end of a vertical shaft 45 (dotted lines, Fig. 1) which has bearings in the lowest cross-bar 14 in which it is both rotatable and slidable. At the lower end of the shaft 45 is mounted the gear 46 the teeth 85 of which are in mesh with the teeth of a pinion 47 mounted on the lower end of the shaft 37. The gears 46 and 24 are of equal pitch, as are the pinions 47 and 38, wherefore it will be apparent that upon rotation 90 of the driving shaft 18 the shafts 45 and 23, and therefore the platform 43 and the chuck 22, will be constantly rotated at equal velocities. The hub 44 of the platform-disk 43 rests—preferably through the interposition 95 of suitable anti-friction devices—upon a collar 48 loose on the shaft 45, which collar, in turn, rests upon a boss 49 on the cross-bar 14. The lower face of the collar 48 is provided with cam surfaces coöperating in a 100 common and well known manner with complementary cam surfaces at the upper end of the boss 49 (as shown and described in my co-pending application aforesaid) to raise and lower said collar 48 upon rotation 105 thereof, in one direction or the other. Projecting to accessible position from the collar 48 is the arm or lever 50, and it will be apparent that a work unit having been positioned on the platform 43, the arm or lever 110 50 may be swung to rotate the collar 48 and raise said platform and therewith said work unit to engagement with the chuck 22. The arm or lever 50, after completion of the 115 seaming operation, is returned to its initial position, thereby lowering the platform to permit of withdrawal of the headed can and the positioning of a new work unit.

To give flexibility to the can engaging parts, I prefer that the cross-bar 14 be not 120 secured to the rods or posts 11 and 12, but rest upon the gear-box 34 which is mounted on said rods or posts through the interposition of coil-springs 51 and 52 in compression between the top of said gear-box and fixed 125 130

collars 53 and 54 at the ends of said rods or posts, respectively.

As is the case with the machine of my co-pending application aforesaid, I prefer that the machine of this application be adapted to be mounted for operation on the edge of a table or bench top, or similar support, and for this purpose I have shown a common and well known type of screw-clamp 55 adapted to be rigidly and removably secured to a support 56 of a character such as that to which I have referred. To the end of the wing or bracket 57 of the clamp is secured the cross-bar 13 of the frame through which the entire machine is supported.

From the foregoing description it will be seen that whether the wheel 19 is rotated continuously or intermittently, reciprocating movement of the seaming rollers is checked when they have reached maximum distances from the chuck, allowing more or less time, as may be required or desired, for the removal of the headed can and the positioning of a new work unit. Immediately following the proper positioning of a new work unit, the rollers may be rapidly returned to effectively operative positions, this operation automatically reestablishing connections with the driving element for the performance of the next succeeding heading operation.

Many modifications of minor details of my improved can heading machine will doubtless readily suggest themselves to those skilled in the art to which it appertains, and I therefore do not desire to limit my invention to the specific construction herein shown and described.

I claim:

40 1. In a machine of the character described, the combination, with means for supporting the assembled parts of a can to be headed, a seaming roller, and means for effecting relative rotary movement between said roller and the portions of the supported can parts to be joined, of means for advancing and retracting said roller to and from effectively coöperative positional relation to said supporting means, said advancing and retracting means including a connection effective throughout a portion only of a cycle of operations, and means manually operable to complete each cycle and restore effectiveness of said connection.

55 2. In a machine of the character described, the combination, with means for supporting the assembled parts of a can to be headed, a plurality of seaming rollers, and means for effecting relative rotary movement between said rollers and the portions of the supported can parts to be joined, of means for advancing and retracting said rollers successively to and from effectively coöperative positional relation to said supporting means, said advancing and

retracting means including a connection effective throughout a portion only of a cycle of operations, and means manually operable to complete each cycle and restore effectiveness of said connection.

3. In a machine of the character described, the combination, with means for supporting the assembled parts of a can to be headed, a seaming roller, and means for effecting relative rotary movement between said roller and the portions of the supported can parts to be joined, of means for advancing and retracting said roller to and from effectively coöperative positional relation to said supporting means, said means for effecting relative rotary movement and said advancing and retracting means being each positively driven from common actuating means, means for automatically disconnecting said advancing and retracting means prior to completion of each cycle of operations thereof and when said roller reaches its most retracted position, and means manually operable to complete said cycle and reestablish the connection.

4. In a machine of the character described, the combination, with means for supporting the assembled parts of a can to be headed, a plurality of seaming rollers, and means for effecting relative rotary movement between said rollers and the portions of the supported can parts to be joined, of means for advancing and retracting said rollers successively to and from effectively coöperative positional relation to said supporting means, said means for effecting relative rotary movement and said advancing and retracting means being each positively driven from common actuating means, means for automatically disconnecting said advancing and retracting means prior to completion of each cycle of operations thereof and when said rollers reach their most retracted positions, and means manually operable to complete said cycle and reestablish the connection.

5. In a machine of the character described, the combination, with means for supporting and rotating the assembled parts of a can to be headed, and a roller adapted to coöperate therewith to perform the seaming operation, of means for advancing and retracting said roller, said advancing and retracting means including a connection effective throughout a portion only of a cycle of operations, and means manually operable to complete each cycle and restore effectiveness of said connection.

6. In a machine of the character described, the combination, with means for supporting and rotating the assembled parts of a can to be headed, and a plurality of rollers adapted to successively coöperate therewith to perform the seaming operation, of means for advancing and retracting

1 said rollers, said advancing and retracting means including a connection effective throughout a portion only of a cycle of operations, and means manually operable to 5 complete each cycle and restore effectiveness of said connection.

2 7. In a machine of the character described, 10 the combination, with means for supporting and rotating the assembled parts of a can to be headed, and a roller adapted to cooperate therewith to perform the seaming operation, of means for advancing and retracting said roller, said supporting and rotating means and said advancing and retracting means being each positively driven from common actuating means, means for automatically disconnecting said advancing and retracting means prior to completion of each cycle of operations thereof and when 15 said roller reaches its most retracted position, and means manually operable to complete said cycle and reestablish the connection.

25 8. In a machine of the character described, the combination, with means for supporting and rotating the assembled parts of a can to be headed, and a plurality of seaming rollers adapted to successively cooperate therewith to perform the seaming operation, of 30 means for advancing and retracting said rollers, said supporting and rotating means and said advancing and retracting means being each positively driven from common actuating means, means for automatically disconnecting said advancing and retracting means prior to completion of each cycle of operations thereof and when said rollers reach their most retracted positions, and means manually operable to complete said 35 40 cycle and reestablish the connection.

45 9. In a machine of the character described, the combination, with means for supporting the assembled parts of a can to be headed, a seaming roller, and means for effecting relative rotary movement between said roller and the portions of the supported can parts to be joined, of means for advancing and retracting said roller to and from effectively 50 coöperative positional relation to said supporting means, said advancing and retracting means including a connection effective throughout a portion only of a cycle of operations and operating at comparatively low speed, and means operable at comparatively high speed to complete each cycle and restore effectiveness of said connection.

55 10. In a machine of the character described, the combination, with means for supporting the assembled parts of a can to be headed, a seaming roller, and means for effecting relative rotary movement between said roller and the portions of the supported can parts to be joined, of means for advancing and retracting said roller to and from effectively 60 coöperative positional relation to

65 said supporting means, said advancing and retracting means including a connection effective throughout a portion only of a cycle of operations and operating at comparatively low speed, and means manually operable at comparatively high speed to complete each cycle and restore effectiveness of 70 said connection.

75 11. In a machine of the character described, the combination, with means for supporting the assembled parts of a can to be headed, a plurality of seaming rollers, and means for effecting relative rotary movement between said rollers and the portions of the supported can parts to be joined, of means for advancing and retracting said rollers successively to and from effectively coöperative positional relation to 80 said supporting means, means for automatically disconnecting said advancing and re- 85 tracting means prior to completion of each cycle of operations thereof and when said rollers reach their most retracted positions, said advancing and retracting means operating at comparatively low speed, and means 90 operable at comparatively high speed to complete each cycle and reestablish the connection.

95 12. In a machine of the character described, the combination, with means for supporting the assembled parts of a can to be headed, a plurality of seaming rollers, and means for effecting relative rotary movement between said rollers and the portions of the supported can parts to be joined, 100 of means for advancing and retracting said rollers successively to and from effectively coöperative positional relation to said supporting means, means for automatically disconnecting said advancing and retracting 105 means prior to completion of each cycle of operations thereof and when said rollers reach their most retracted positions, said advancing and retracting means operating at comparatively low speed, and means manually operable at comparatively high speed to 110 complete each cycle and reestablish the connection.

115 13. In a can heading machine, in combination, a chuck, a shaft at the end of which said chuck is mounted, seaming rollers adapted to coöperate with said chuck to perform the seaming operation, means for effecting relative rotary movement between said chuck and said rollers, a sleeve on said 120 shaft, connecting means between said sleeve and said rollers to advance and retract said rollers to and from effectively coöperative positional relation to said chuck upon rotation of said sleeve, and means for rotating 125 said sleeve, said sleeve-rotating means including a connection effective throughout a portion of a cycle of operations, and means manually operable to complete each cycle and restore effectiveness of said connection. 130

14. In a can heading machine, in combination, a chuck, a shaft at the end of which said chuck is mounted, seaming rollers adapted to coöperate with said chuck to perform the seaming operation, means for effecting relative rotary movement between said chuck and said rollers, a sleeve on said shaft, connecting means between said sleeve and said rollers to advance and retract said rollers successively to and from effectively coöoperative positional relation to said chuck upon rotation of said sleeve, means for rotating said sleeve, said sleeve rotating means including a connection effective throughout a portion only of a cycle of operations and operating at comparatively low speed, and means operable at comparatively high speed to complete each cycle and restore effectiveness of said connection.
15. In a can heading machine, in combination, a chuck, a shaft at the end of which said chuck is mounted, seaming rollers adapted to coöperate with said chuck to perform the seaming operation, means for effecting relative rotary movement between said chuck and said rollers, a sleeve on said shaft, connecting means between said sleeve and said rollers to advance and retract said rollers successively to and from effectively coöoperative positional relation to said chuck upon rotation of said sleeve, means for rotating said sleeve, said sleeve rotating means including a connection effective throughout a portion only of a cycle of operations and operating at comparatively low speed, and means manually operable at comparatively high speed to complete each cycle and restore effectiveness of said connection.
16. In a can heading machine, the combination, with a driving element, of a chuck, a shaft at the end of which said chuck is mounted, seaming rollers adapted to coöperate with said chuck to perform the seaming operation, means actuated from said driving element for effecting relative rotary movement between said chuck and said rollers, a sleeve on said shaft, connecting means between said sleeve and said rollers successively to advance and retract said rollers to and from effectively coöoperative positional relation to said chuck upon rotation of said sleeve, means also actuated from said driving element for rotating said sleeve, means for automatically disconnecting said sleeve-rotating means prior to completion of each cycle of operations thereof and when said rollers reach their most retracted positions, and means manually operable to complete said cycle and reëstablish the connection.
17. In a can heading machine, the combination, with a driving element, of a chuck, a shaft at the end of which said chuck is mounted, seaming rollers adapted to coöperate with said chuck to perform the seaming operation, means actuated from said driving element for effecting relative rotary movement between said chuck and said rollers, a sleeve on said shaft, connecting means between said sleeve and said rollers to advance and retract the latter to and from said chuck upon rotation of said sleeve, means for rotating said sleeve independently of said shaft, said sleeve-rotating means including a connection effective throughout a portion only of a cycle of operations, and means manually operable to complete each cycle and restore effectiveness of said connection.
18. In a can heading machine, the combination, with a driving element, of a chuck, a shaft at the end of which said chuck is mounted, seaming rollers adapted to coöperate with said chuck to perform the seaming operation, means actuated from said driving element for effecting relative rotary movement between said chuck and said rollers, a sleeve on said shaft, connecting means between said sleeve and said rollers to advance and retract said rollers successively to and from effectively coöoperative positional relation to said chuck upon rotation of said sleeve, means also actuated from said driving element for rotating said sleeve, said sleeve-rotating means including a connection effective throughout a portion only of a cycle of operations and operating at comparatively low speed, and means manually operable at comparatively high speed to complete each cycle and restore effectiveness of said connection.
19. In a can heading machine, the combination of a chuck, a shaft at the end of which said chuck is mounted, seaming rollers adapted to coöperate with said chuck to perform the seaming operation, means for rotating said shaft, a sleeve on said shaft, connecting means between said sleeve and said rollers to advance and retract the latter to and from said chuck upon rotation of said sleeve, means for rotating said sleeve independently of said shaft, said sleeve-rotating means including a connection effective throughout a portion only of a cycle of operations, and means manually operable to complete each cycle and restore effectiveness of said connection.
20. In a can heading machine, the combination of a chuck, a shaft at the end of which said chuck is mounted, seaming rollers adapted to coöperate with said chuck to perform the seaming operation, means for rotating said shaft, a sleeve on said shaft, connecting means between said sleeve and said rollers to advance and retract the latter successively upon rotation of said sleeve, means for rotating said sleeve independently of said shaft, said sleeve-rotating

- means including a connection effective throughout a portion only of a cycle of operations and operating at comparatively low speed, and means operable at comparatively high speed to complete each cycle and restore effectiveness of said connection. 65
21. In a can heading machine, the combination of a chuck, a shaft at the end of which said chuck is mounted, seaming rollers adapted to coöperate with said chuck to perform the seaming operation, means for rotating said shaft, a sleeve on said shaft, connecting means between said sleeve and said rollers to advance and retract the latter successively to and from said chuck upon rotation of said sleeve, means for rotating said sleeve independently of said sleeve-rotating means including a connection effective throughout a portion only of a cycle of operations and operating at comparatively low speed, and means manually operable at comparatively high speed to complete each cycle and restore effectiveness of said connection. 70
22. In a can heading machine, the combination, with a driving element, of a chuck, a shaft at the end of which said chuck is mounted, seaming rollers adapted to coöperate with said chuck to perform the seaming operation, means actuated from said driving element for rotating said shaft, a sleeve on said shaft, connecting means between said sleeve and said rollers to advance and retract said rollers successively to and from said chuck upon rotation of said sleeve, means also actuated positively from said driving element for rotating said sleeve independently of said shaft, means for automatically disconnecting said sleeve-rotating means prior to completion of each cycle of operations thereof and when said rollers reach their most retracted positions, and means manually operable to complete said cycle and reestablish the connection. 75
23. In a can heading machine, in combination, a chuck, a shaft at the end of which said chuck is mounted, seaming rollers adapted to coöperate with said chuck to perform the seaming operation, means for effecting relative rotary movement between said chuck and said rollers, a sleeve on said shaft, connecting means between said sleeve and said rollers to advance and retract said rollers to and from said chuck upon rotation of said sleeve, means for rotating said sleeve, said means comprising a reciprocating pawl and a mutilated ratchet on said sleeve whereby pawl-driven movement of said sleeve is less than one revolution thereof, and means for continuing movement of said sleeve to complete one revolution and bring the teeth thereof again into engagement with said pawl. 80
24. In a can heading machine, in combination, a chuck, a shaft at the end of which said chuck is mounted, seaming rollers adapted to coöperate with said chuck to perform the seaming operation, means for rotating said shaft, a sleeve on said shaft, connecting means between said sleeve and said rollers to advance and retract said rollers to and from said chuck upon rotation of said sleeve, means for rotating said sleeve independently of said shaft, said means comprising a reciprocating pawl and a mutilated ratchet on said sleeve whereby pawl-driven movement of said sleeve is less than one revolution, and means manually operable at will for continuing movement of said sleeve to complete one revolution and bring the teeth thereof again into engagement with said pawl. 85
25. In a can heading machine, in combination, a chuck, a shaft at the end of which said chuck is mounted, seaming rollers adapted to coöperate with said chuck to perform the seaming operation, means for rotating said shaft, a sleeve loose on said shaft, connecting means between said sleeve and said rollers to advance and retract the latter to and from said chuck upon rotation of said sleeve, means for rotating said sleeve independently of said shaft, said means comprising a reciprocating pawl and a mutilated ratchet on said sleeve whereby pawl-driven movement of said sleeve is less than one revolution, and means for continuing movement of said sleeve to complete one revolution and bring the teeth thereof again into engagement with said pawl. 90
26. In a can heading machine, in combination, a chuck, a shaft at the end of which said chuck is mounted, seaming rollers adapted to coöperate with said chuck to perform the seaming operation, means for rotating said shaft, a sleeve loose on said shaft, connecting means between said sleeve and said rollers to advance and retract the latter to and from said chuck upon rotation of said sleeve, means for rotating said sleeve independently of said shaft, said means comprising a reciprocating pawl and a mutilated ratchet on said sleeve whereby pawl-driven movement of said sleeve is less than one revolution, and means manually operable at will for continuing movement of said sleeve to complete one revolution and bring the teeth thereof again into engagement with said pawl. 95
- In testimony of the foregoing, I have hereunto set my hand in the presence of two witnesses.

JULIUS BRENZINGER.
